UNITED STATES PATENT OFFICE.

GEORGE G. PORTER, OF SYRACUSE, NEW YORK.

TOOL-POST.

1,396,461.

Specification of Letters Patent.

Patented Nov. 8, 1921.

Application filed October 7, 1919. Serial No. 329,408.

To all whom it may concern:

Be it known that I, GEORGE G. PORTER, a citizen of the United States, and a resident of Syracuse, in the county of Onondaga and 5 State of New York, have invented a certain new and useful Tool-Post, of which the following is a specification.

This invention has for its object a particularly rigid simple tool post for engine 10 lathes, in which the tools can be more readily secured than in the ordinary tool post and which will also have an increased capacity for taking larger tools. Another object of the invention is to effect a saving in tools by 15 providing a tool post which will hold boring tools or other tools with round shanks as well as the ordinary turning tools or tool holders with square or rectangular shanks, and without bruising or distorting the 20 shanks of said tools as is done with the tool posts now in use, wherein the end of the tool post screw comes directly in contact with the shank of the tool. A further object of the invention is to provide a tool post in 25 which adjustments of the tool for height, and certain other adjustments can be readily made without releasing the tool from said tool post or disturbing its setting after it has been rigidly secured therein, as will be 30 hereinafter more fully set forth.

The invention consists in the novel features and in the combinations and constructions hereinafter set forth and claimed.

In describing this invention, reference is 35 had to the accompanying drawings, in which like characters designate corresponding parts in all the views.

Figures 1 and 2 are respectively, a plan view and a vertical sectional view of a preferable embodiment of this tool post as arranged when used for holding boring tools, Fig. 2 being taken on line 2—2, Fig. 1 and looking in the direction of the arrows.

Fig. 3 is a plan view similar to Fig. 1 45 showing my tool post arranged when holding a cutting tool for external turning operations.

This tool post comprises generally, a body 50 adjustable about an upright axis, a slide carried by the body and adjustable vertically relatively thereto, the slide being provided with means for holding the tool, and means for holding the body and the slide in their adjusted positions.

1 designates the body which is here shown 55 as tubular, that is, it is formed with a cylin-

drical shaped passage 2, and dove-tail vertical ways 3.

4, 5 are discoidal bearings or locating members which fit loosely into the upper and 60 lower ends of the passage 2 and about the axis of which the body 1 is adjustable, the bearings 4, 5 being here illustrated as being mounted in the counterbored bearings 6 and 7 at the ends of the passage 2. The members 65 keep the body in its proper location on top of the cross slide 11, and with reference to the clamp bolts 12. The upper disk 4 is formed with a flange 8 overlapping the top 70 face of the body 1. This disk serves as a washer for the bolts 12 and as a clamping member to secure the tool post rigidly to the cross-slide 11.

9 is a base or T nut having two tapped holes, which fits into the T slot 10 of the 75 cross-slide 11 of the tool carriage of a lathe, as will be understood by those skilled in the art.

As here illustrated, the body is secured to the slide 11 by means of threaded studs 80 12 extending through the disks 4, 5 and threading into the nut 9, and nuts 13 threading on the upper ends of the studs against the upper disk 4. There are preferably two studs both of which are located out of 85 the axis of the body 1, so as to bring the cutting tool as close as possible to the top of the cross-slide 11.

14 is the slide having a dovetail way 15 movable in the ways 3 of the body 1, this 90 slide being formed with means for receiving the shank 16 of the tool as a transverse slot or passage 17. It is also formed with means for clamping the shank 16 of the tool, this means being here shown as a clamping member 95 or sliding block 18 movable to clamp the tool 16 by means of screws 19 threading into the member 14 through the top thereof, the screws projecting into the passage 17 and bearing against the upper face of the 100 sliding block or clamping member 18.

This member 18 is moved in the other direction, that is, upwardly away from the tool 16 by means of a tension spring 20 located in suitable aligned passages 21, 22 in the 105 slide 14 and the member 18, the opposite ends of the spring being connected respectively to pins or rods 23, 24 extending transversely through the passages 21 and 22 respectively.

The object of the clamping member 18 is 110 to provide means for keeping the shanks of

the tools from being mutilated or bent by the action of the ends of the set screws 19 as is the case in the ordinary tool post, wherein the screw comes directly in contact with the shank of the tool. The block 18 is preferably made comparatively thick and is a sliding fit in the slot 17 which keeps it from cramping in the slot 17 even when it rests on the shank of a tool which is held to one side of the slot as shown in Fig. 3.

32 represents a piece which is held in a lathe in a chuck or other suitable means and in proper position for boring. The line 33 represents the center line of the spindle of the lathe. 34 indicates a piece turning on centers in the lathe in the usual manner and driven by the dog 35.

It is well known to those skilled in the art, that when clamping a boring tool with a round shank in a V block in an ordinary tool post, that the end of the screw 30 bruises the shank of the tool and bends it as shown somewhat exaggerated, in Fig. 4, so that the tool is really insecurely held between three pivotal points, viz. the end of the screw and that portion of the V block directly underneath. Also when using turning tools with rectangular shanks for taking heavy cuts the tools often swing around under the end of the single set screw and result in spoiled work. In my tool post, these faults are overcome by using two set screws instead of one, as shown, which gives the tools a much more rigid support than is possible with the old style tool post.

The slide is moved upwardly by means of a screw 25 threading through the lug 26 at the upper end of the slide 14 and overhanging the body 1.

40 The slide 14 is held in its adjusted position by clamping screws 27 extending transversely through the body and acting to clamp the walls of the channel or way 3 onto the dovetail way 15 of the slide 14.

45 As here shown, the body is split from end to end or divided longitudinally by the slot 28, which allows the screws 27 that extend transversely through the body into the sections thereof on opposite sides of the slot 28; and are threaded into one section of the body, to bind the body and slide together.

The V block, as shown in Fig. 2 is used when holding tools with round shanks. It can also be turned up side down from the position shown and used as a filler block when holding very small tools with square shanks.

When using the ordinary turning tools with rectangular shanks as in Fig. 3, the 60 filler block 29 is not used. But the tool is held directly between the bottom of the slot and the clamping member 18.

Tool posts of the ordinary type, as shown by Figs. 4 and 5, when made for medium size lathes will only hold tools with shanks

from $\frac{1}{2}$ to $\frac{5}{8}$ inch in width, and the slot 31 is not usually of sufficient height to allow any filler block to be placed between the ends of the set screw and the boring tool, to keep the boring tool from becoming bent and bruised. 70 With my tool post made as shown, of proper size for the same lathes, round or rectangular tools having a shank one inch in diameter or width can be used and without the shanks of the tools becoming bruised or bent. 75 This greatly increases the range of the tool post especially for holding boring tools, as when it is desirable to bore large holes where a great deal of stock is to be removed and a heavy rigid boring bar is in order, it 80 is not necessary to resort to some other method for holding the tools as is the case with the ordinary tool post.

In operation, the tool is placed in the passage 17 and held there by the clamping block 85 18 using the V-block 29 if desirable as previously described. If the cutting lip of the tool is not at the proper height the tool and slide can be raised or lowered by loosening the clamp screws 27 and turning the screw 90 25 in the proper direction until the desired height is obtained. The screws 27 are then tightened to bind the body and slide together.

The angular position of the tool is determined by loosening the nuts 13 on the studs 12 and adjusting the body 1 about the locating members or bearings 4 and 5. The diameter of the bearings 4 and 5 is such that they are comparatively loose fit in the body 100 so that they are not clamped by the clamp screws 27 which hold the slide 14 in its adjusted position. This permits of the slide being in proper position for height and secured to the body and then allowing the angular adjustment to be made about the vertical axis without disturbing the height of the tool. 105

As will be seen by those skilled in the art, my tool post can be used for holding either 110 tools with round or rectangular shanks and tools for either boring or turning and will hold the tools very rigidly so that much heavier cuts may be taken without causing chatter in the work.

At times it will be found more convenient to swing the tool post through an angle of about 180° from that shown in Fig. 3, and use the turning tool, the cutting end of which would then protrude from the side 120 36, in other words, the cutting end of the tool would be on the opposite end of the shank from what it is shown in Fig. 3.

What I claim is:

1. A tool post comprising a tubular body, 125 a base, disks located in opposite ends of the tubular body, a screw extending through the disks and into the base, and tool holding means associated with the body, substantially as and for the purpose described. 130

2. A tool post comprising a tubular body, a base, disks located in opposite ends of the tubular body, a screw extending through the disks and into the base, the screw being located eccentric to the axis of the body, and tool holding means associated with the body, substantially as and for the purpose specified.
3. A tool post comprising a tubular body, a base, disks located in opposite ends of the tubular body, a pair of screws extending through the disks and into the base, and tool holding means associated with the body, substantially as and for the purpose set forth.
4. A tool post comprising a tubular body divided longitudinally along one side and formed with vertical ways along one side, the line of division opening through the bottom of the way, disks mounted in opposite ends of the tubular body, a base and means extending through the disks and into the base, a slide adjustable in the ways and having means for holding the tool, and clamping means extending transversely through the body adjacent the ways for clamping the body onto the slide and holding the slide in its adjusted position, substantially as and for the purpose specified.
5. A tool post comprising a tubular body split longitudinally along one side thereof and formed with vertical ways along such side, the plane of division opening through the bottom of the way, a base, and means carried by the base and located in the tubular body and about which the tubular body is adjustable, a slide adjustable in the ways and having means for holding the tool and clamping means extending transversely through the body crosswise of the split adjacent the ways for clamping the body onto the slide and holding the body in position relatively to the base, substantially as and for the purpose described.
6. A tool post comprising a tubular body, a slide carried by the body and movable vertically relatively thereto, a base, a bearing member arranged in the tubular body, and means rising from the post and engaging the bearing member, substantially as and for the purposes specified.
7. A tool post comprising a tubular body, a slide carried by the body and adjustable vertically relatively thereto, and having means for holding the tool, disks mounted on opposite ends of the body, a base and clamping means extending through the disks and into the base, substantially as and for the purpose set forth.

In testimony whereof, I have hereunto signed my name at Syracuse, in the county of Onondaga, and State of New York, this 16th day of Sept., 1919.

GEORGE G. PORTER.
